UNITED STATES PATENT OFFICE.

THOMAS R. JENKINS, JR., OF BALTIMORE, MARYLAND, ASSIGNOR OF ONE-HALF TO WALTER S. FINNELL, OF HANNIBAL, MISSOURI, AND ONE-HALF TO FINOLA MANUFACTURING COMPANY, OF HANNIBAL, MISSOURI, A CORPORATION OF MISSOURI.

ROTARY SCRUBBING-MACHINE.

1,079,298.

Specification of Letters Patent. Patented Nov. 18, 1913.

Application filed January 18, 1912. Serial No. 671,958.

To all whom it may concern:

Be it known that I, THOMAS R. JENKINS, Jr., a citizen of the United States, residing at Baltimore, in the State of Maryland, have invented certain new and useful Improvements in Rotary Scrubbing-Machines, of which the following is a specification.

This invention relates to improvements in rotary scrubbing machines and has particular reference to that class of machines wherein the scrubbing brushes are sustained from a wheeled frame and are rotated as the frame is wheeled over the surface that is to be scrubbed.

The present invention has particular reference to that part of a scrubbing machine which sustains the brushes during rotation.

The invention resides in the novel features of construction hereinafter described and particularly set forth in the claims.

Certain features relating to the brushes and their retaining parts which are shown and described herein are made the subject of a companion application Serial No. 671,959 filed January 18th, 1912 and are therefore not claimed herein.

The invention is illustrated in the accompanying drawings whereof,

Figure 1, shows the improved brush-carrying devices in side elevation and the mechanism for driving the same. Fig. 2, is a top plan view of the same; Fig. 3, is a vertical cross-section through the same. Fig. 4, shows an enlarged sectional detail through the carrier ring and a side elevation of a brush attached thereto. Fig. 5, is a perspective detail of the brush-plate, and Fig. 6, an enlarged detail plan view of a portion of the carrier ring.

Referring to the drawings by numerals, 1, designates a short horizontal axle on the outer ends of which are carried suitable wheels, 2. These wheels are loosely mounted on the ends of the axle and are preferably provided with rubber tires, 3. Midway between the wheels the axle has a circular flat bearing or seat, 4, and a central stem, 5, projects vertically from this seat. The stem, 5, sustains a circular plate, 6, which latter has a central perforation that receives a downwardly-extending hub, 7, through which the stem projects, as will presently be more fully described so that the said hub,

7, and plate, 6, may turn on the stem. The plate is provided with a plurality of outwardly-projecting and downwardly-curved arms, 8, each of which latter has a threaded perforation, 9, in its outermost end. In the present instance the plate is provided with four arms but obviously the number may be more or less than shown. Each arm, 8, carries a bolt, 10, which engages the threads in the perforations, 9, and which depends below the said arms, for a purpose presently to be described.

A ring-plate, 11, encircles the wheels, 2, and has position in a horizontal plane below the arms and said ring-plate is provided with arms, 12, that project inwardly toward the wheels from the inner circumferential edge of the ring plate. The inner ends of these arms, 12, are also provided with perforations, 13, which latter have position directly beneath the perforations, 9, in the arms, 8, so that the lower pendant ends of the bolts, 10, may pass freely therethrough and thus loosely connect the ring plate with the arms, 8, of the circular plate, 6. Suitable nuts, 14, on the lower ends of bolts, 10, prevent accidental disengagement of the ring plate but enable the same to be disengaged when desired and springs, 40, encircle the bolts and have their upper ends seated against washers, 41, while their lower ends seat on the arms, 12.

The ring plate is provided at intervals with openings, 15, and each opening has a flange, 16, which extends vertically from the upper surface of the ring plate. In the present instance there are eight openings, 15, in the ring plate, but the number is immaterial and is only determined by the number of brush sections it is desired to use, as will presently be explained.

On both sides of each opening, 15, the ring-plate is provided with upwardly-projecting hollow bearings or casings, 17, the upper ends of which have a perforation which forms a bearing as and for a purpose presently to be explained.

Suitable webs, 18, and, 19, respectively are provided on the ring-plate and the arms thereof for the purpose of stiffening and strengthening the same.

The purpose of the ring-plate is to loosely sustain or carry the brushes and as the con-

nections between these parts are found to be very effective in practice they will now be described in detail.

5 A plurality of brushes, 20, are employed and each brush has a brush block, 21, in the bottom of which the bristles are secured in any suitable manner. The brush blocks also have a central perforation, 22, through which a bolt, 23, extends, as shown in broken 10 lines in Fig. 4, and the upper surface of each block has a cavity or recess, 24, at opposite sides of the bolt, 23.

15 A brush suspension plate, 25, is interposed between the upper side of the brush block, 21, and the bottom side of the ring-plate, 26, and each plate has a central perforated boss, 27, at the outer side of the boss which rib extends from the top surface of the boss to the bottom edge of 20 the plate, as clearly seen in Fig. 5. It will also be noted by reference to Fig. 5, that the suspension plate, 25, is curved from one end to the other and that said curvature conforms to the curvature of the ring plate.

25 At each end the suspension plate, 25, is provided with vertically-projecting pins, 28, which are so spaced from the central boss that when the plate is seated against the under side of the ring plate with the boss in 30 the opening, 15, the pins will extend vertically through the hollow bearings or casings, 17, on the ring-plate so their upper ends will project through the perforations at the upper ends of the casings. Cotter pins, 29, are inserted in the ends of the pins, 28, and prevent the latter from dropping downwardly and out of the casings.

35 It will thus be seen that the ring-plate is loosely sustained below the circular plate, 6, and is free to have vertical movement on the bolts, 10, and that the brush-suspension plates, 25, are loosely sustained from the ring-plate and are free to move vertically independently thereof. There is a decided 45 advantage in this construction where floor surfaces have hollows or raised places therein because each suspension plate is capable of movement independently of all the other plates.

50 By reference to Fig. 4, it will be seen that the bottom side of the suspension plate, 25, has short projections or lugs, 30, and that the brush block is fitted up close against the bottom side of the suspension plate so that the projections or lugs, 30, will enter the cavities or recesses, 24, at opposite sides of the bolt, 23, while said bolt passes up through the boss, 26, and is held therein by means of a wing nut, 31.

55 From the foregoing explanation it will be understood that the nut, 31, will hold the brush block and suspension plate together at the center while the projections, 30, will enter cavities, 24, and prevent the block 60 from turning on the bolt. Also it will be

noted that the two pins, 28, on the suspension plate will prevent the latter from twisting with respect to the ring-plate.

65 By again referring to Fig. 4, it will be noted that the hollow bearings or casings, 17, through which the pins, 28, extend each contain a coiled spring, 32, and that these springs encircle the pins and are compressed between the upper ends of the casings and the upper surfaces of the brush-suspension plates, 25. By this means a yielding downward pressure is exerted continually on the plates, 25, so as to press the brushes downward in contact with the floor surface. As the brushes are formed in sections each section has a vertical movement independently of all the other sections and also independently of the ring plate, consequently slight hollows or raised places in a floor surface will receive the same scrubbing 75 action that the level surfaces will receive.

80 By providing the rib, 27, on the boss, 26, lateral rocking of the suspension plate, 25, is avoided and uneven wear on the brushes reduced to a minimum, but at the same time 90 the said plates, 25, may have a slight rocking motion from end to end to allow the brush to ride over any uneven spots on a floor.

85 A machine employing the structure above 95 described is provided with a suitable driving shaft, 33, on which a pinion, 34, is mounted and this pinion meshes with and drives a horizontal gear, 35, that is secured by bolts, 36, on top of the circular plate, 6. 100

90 The hub, 7, depends from the gear, 35, and passes through a central opening in the circular plate, 6, as clearly seen in Fig. 3 of the drawing.

95 A frame, 37, has an eye, 38, that receives 105 the upper end of stem, 5, and a nut, 39, secures the stem to the frame. The frame, 37, is a part of the machine which forms no part of the present invention and which is substantially like that shown in a pending 110. application, Serial Number 525,024 filed by me on the 28th day of October 1909.

105 Having thus described my invention what I claim and desire to secure by Letters Patent is,—

110. 1. In a brush carrying mechanism for 115 scrubbing machines the combination with a ring plate having a plurality of spaced-apart hollow casings and an opening between adjacent casings, of a plurality of brush suspension plates each having spaced-apart stems which project into the said hollow casings,—said suspension plates also having an opening therein between the stems; a brush for each suspension plate and means in the openings between the hollow casings for securing the brushes to their suspension plates.

120 2. In a brush carrying mechanism for 125 scrubbing machines the combination with a

ring plate having a plurality of spaced-apart hollow casings each with an opening and also having an opening in the plate between adjacent casings, of brush suspension

5 plates having spaced-apart stems which project into and through the hollow casings and said suspension plates each also having a perforated boss on its upper side between the stems and each boss having a vertical rib on
10 one side; a brush secured to the boss of each

of the suspension plates and the boss and rib of each suspension plate entering one of said openings of the ring plate between the casings.

In testimony whereof I affix my signature 15 in presence of two witnesses.
